UNITED STATES PATENT OFFICE.

CRAWFORD P. McGINNIS AND CHARLES W. DAKE, OF CHICAGO, ILLINOIS, ASSIGNORS TO THE PYLE-NATIONAL COMPANY, OF CHICAGO, ILLINOIS, A CORPORATION OF NEW JERSEY.

CAB LAMP.

Application filed December 5, 1923. Serial No. 672,586.

To all whom it may concern:

Be it known that we, CRAWFORD P. McGINNIS and CHARLES W. DAKE, being citizens of the United States, and residents of Chicago, in the county of Cook and State of Illinois (whose post-office address is 1334 North Kostner Avenue, Chicago, Illinois), have invented a certain new and useful Improvement in Cab Lamps, of which the following is a specification.

Our invention relates to improvements in electric lights for use in connection with railroad locomotive cabs for furnishing light to illuminate gauges, dials and the like. It has for one object to provide a new and improved light which can be easily adjusted in position, wherein the electric light bulb may be protected and at the same time easily removed for renewal and wherein the light can be concentrated in a controlled ray so as to light up only the part which is to be illuminated and prevent glare which would interfere with the engineer and fireman and make it impossible for them to see signals from the outside. Other objects will appear from time to time in the specification.

Our invention is illustrated more or less diagrammatically in the accompanying drawings, wherein—

Figure 1 is a section through the lamp;
Figure 2 is an elevation.

Like parts are indicated by like characters throughout the specification and drawings.

A is the cab wall or any other suitable stanchion or support. A¹ is a bracket bolted thereto. This bracket terminates in a spherical centrally apertured member A². A³ is a curved washer adapted to ride on the outside thereof. Passing through this washer and through the aperture is a cap screw A⁴ which is screw threaded into a foot A⁵ having a spherical surface to engage the inside of the member A². A⁶ is a lamp support or base integral with the foot A⁵, flanged at A⁷ and provided with a rearwardly extending threaded hollow boss A⁸.

B is an electric light socket threaded into the support A⁶, the support being apertured to make this possible. B¹ is a socket within the lamp support closed by the base B to leave room for the electric conductors B², B³

which pass inwardly through the conduit B⁴ threaded in the boss A⁸, and terminate at the electric light base B.

C is a housing of metal or other suitable material. It is relatively stiff and rigid and preferably opaque though it might be more or less translucent. It is carried on the outside of the annular ring A⁷ and has a plurality of bayonet joint slots C¹ associated with the pins C² on the ring A⁷ and has a boss C³ engaged by a screw C⁴ threaded in the ring A⁷ to hold the parts together and prevent unintentional disengaging of the bayonet joints. C⁵ is a reflector located inside the housing C having a curved surface associated with the electric light bulb B⁵. This reflector is adjustably mounted on the wall of the housing C by the bolt C⁶.

Opposite the reflector C⁵, the housing C is apertured as at D and the wall of the housing forms a cylindrical barrel D¹ in line with this aperture. D² is a lens cell slidable in the barrel D¹ and held in position thereon by a screw D³. The outer end of this cell carries a lens D⁴ through which pass the direct light rays from the light source or the bulb as well as reflected rays from the reflector. This arrangement of barrel, lens and reflector insures that there will be a minimum of defused light, that the light ray or beam will be directed only upon the element which it is desired to illuminate.

It will be evident that while we have shown in our drawings an operative device still many changes might be made in the size, shape and arrangement of parts without departing materially from the spirit of our invention and we wish, therefore, that our drawings be regarded as in a sense diagrammatic.

The use and operation of our invention are as follows:

The electric bulb and the exposed electrical connection between it and the base are entirely enclosed within the continuous housing. This housing being more or less rigid and stiff prevents accidental breakage of the bulb itself, protects the surface of the bulb and electrical connections from dirt, dust, moisture and the like and makes it necessary only to clean the small rigid and durable lens. The conduit associated

with the base protects the wiring and there is little danger of short circuiting or lamp trouble. The ball and socket mounting for the lamp makes it possible to direct the ray 5 of light in any desired direction within reasonable limits by loosening the cap screw and moving the base and washer in any desired direction, limited only by the size of the aperture in the bracket to properly 10 position the light.

The cylindrical extension containing the lens cell together with the lens itself and reflector prevent the diffusion of light rays and insures that the light will be directed 15 in a concentric parallel beam from the light source upon the object, such as indicator, gauge or dial, which it is desired to illuminate. By using the reflector and the lens it is possible to get a beam of considerable 20 intensity. This makes it possible to illuminate objects from a light source placed at a distance so that it is not necessary to have the light itself immediately adjacent the object to be illuminated.

25 We claim:

1. A cab lamp comprising a base on which a light source may be mounted, a rigid, opaque housing closely surrounding the light source and removably mounted on the 30 base, a cylindrical projection from one side of the housing and a lens cell removably mounted therein, a reflector adjustably mounted within the housing on the wall thereof behind the light source and in line 35 with the lens cell.

2. A cab lamp comprising a base, a lamp supporting sleeve threaded therein, a per-

foration extending through the base communicating with the aperture in which the lamp supporting sleeve is threaded, a conduit 40 communicating with such perforation, a light source threaded in the supporting sleeve, a flange on the base, an opaque housing removably mounted on the flange enclosing the light source, a cylindrical projection 45 on one side of the housing and a lens cell removably socketed therein, a foot projecting from the base, a spherical portion engaging the foot and means for locking the two together in adjusted position, and a reflector contained within the housing in line with the lens socket mounted on the wall of the housing.

3. A cab lamp comprising a base on which a light source may be mounted, a rigid 50 opaque housing closely surrounding the light source, and removably mounted on the base, a supporting bracket for said base, a light socket threaded in the base, a light 55 source threaded in the socket, a conduit independent of the bracket leading from the base, and electric conductors therein 60 terminating at the light socket, a cylindrical projection from one side of the housing, and a lens cell removably mounted therein, and 65 a reflector mounted within the housing on the wall thereof behind the light source and in line with the lens cell.

Signed at Chicago, County of Cook and State of Illinois, this 30th day of November, 70 1923.

CRAWFORD McGINNIS.
CHARLES W. DAKE.
